UNITED STATES PATENT OFFICE.

FRANK E. MODLIN, OF FORT WORTH, TEXAS.

GAS-PRODUCER.

1,295,188.

Specification of Letters Patent. Patented Feb. 25, 1919.

Application filed June 1, 1918. Serial No. 237,747.

To all whom it may concern:

Be it known that I, FRANK E. MODLIN, a citizen of the United States, residing at Fort Worth, in the county of Tarrant and State of Texas, have invented a new and useful Gas-Producer, of which the following is a specification.

This invention relates to gas producers, and contemplates the provision of a structure for the production of gas which will be simple, durable, and efficient in operation, permitting the use of cheap fuel, such as lignite, in the manufacture of gas.

A main object of the invention is the provision of means for converting by-products, such as coal-tar and creosote, into gas.

Another object of the invention is the provision of means for feeding the fuel evenly to the fire bed.

20 A still further object is the provision of a superheater for the gas.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 25 the scope of what is claimed without departing from the spirit of the invention.

A practical embodiment of the invention is shown in the accompanying drawings, wherein:—

35 Figure 1 is a central vertical section of a producer constructed in accordance with the invention;

Fig. 2 is a cross section on the line 2—2 of Fig. 1, viewed in the direction of the 40 arrows;

Fig. 3 is a section on the line 3—3 of Fig. 1;

Fig. 4 is a plan view of the superheater;

Fig. 5 is a central cross section of the 45 same.

Referring to the drawings by numerals of reference:—

In carrying out the invention there is provided a base section or drum 1 which 50 forms an ash pit and draft chamber, at which is provided with an opening normally closed by the usual ash and draft door 2. A grate 3 of any usual and preferred type is supported on the drum 1.

55 Seated upon the drum 1 is an upright,

double walled drum 4 the spaced inner and outer walls of which provide a water space 5 for the purpose of protection. This drum 4 constitutes the fire pot and collection chamber or retort of the device.

60

Depending within the drum 4 and spaced from the inner wall thereof, is an inverted frusto-conical tubular feeder 6 the lower end of the wall of which is formed with radially disposed out-struck hoods 7 which communicate with the interior of the tubular feeder. The lower end of this feeder terminates just above the fire bed and its upper end is secured by rivets or otherwise to the annular supporting member 8, 65 formed with an outturned flange 9 which flange rests upon a ring 10 seated on the drum 4 and through which ring the annular support 8 projects.

70

A tubular container 11 has its lower end 75 threaded into or otherwise secured to the support 8 and its upper end is formed with a flaring mouth or hopper 12. The container 11 is provided with spaced transverse slots through which slide the upper 80 and lower gates 13 and 14, respectively. The upper gate 13 is formed with a radially extending ear which has pivotal attachment to a bracket 15 secured to the side of the container 11. At a diametrically opposed 85 point, a radially extending handle 16 is formed on the gate 13. The lower gate 14 is also provided with a similar ear which has pivotal attachment to a bracket 17, and the gate is likewise provided with a handle 90 18. The handles 16 and 18 allow the upper and lower gates to be successively swung to admit charges of fuel to the lower portion of the container 11.

95

An annular worm wheel 19 encircles the lower end of the container 11, to which it is rigidly secured, and meshes with a worm 20 which is driven by any suitable means (not shown) for the purpose of rotating the container and the feeder 6.

100

Pipes 21 communicate at suitable intervals with the interior of the drum 4, near the upper end of said drum, and converge downwardly about the outside of the drum to take into one end of a super-heater 22 105 which is horizontally arranged above the grate 3 and in position to be embedded in the fire bed. The super-heater 22 is preferably formed with short cylindrical ends between which ends it is flattened to form 110

a hollow, vertically arranged web connecting the ends. From the opposite end of the super-heater 22 a pipe 23 leads to a fourway union 24, access to which may be had 5 through a plug 25 which is threaded into that port or opening of the union or joint opposed to the one into which the pipe 23 is threaded.

To provide a washer and cooler through 10 which the gas may be passed, a cylinder 26, formed with a threaded nipple at its lower end which is threaded into one of the openings or ports of the union 24, rises from the union and within this cylinder is a centrally 15 disposed rod 27 which extends longitudinally of the cylinder, and on which are secured the spaced, conical disks 28 formed with apertures 29. A collar 30 is threaded on the upper end of the cylinder 26 and is 20 closed by a plug 31 which permits access to the cylinder for the purpose of removing the rod 27 and its disks, when the same becomes necessary. An inlet pipe 32 leads through an aperture in the collar 30 and conveys a suitable stream of water to the cylinder, which water, dropping through the apertures 29, tends to wash the ascending gas.

After passing through the cylinder 26 and being washed and cooled, the gas passes 30 through a pipe 36 which is threaded into the collar 30 to a receiving tank or storage tank 37, from which it may be led to any desired point through a pipe 38.

The wash water, after passing through 35 the cylinder 26 and removing the impurities from the gas, passes through a pipe 33 which is threaded into the union 24 and depends therefrom, to a trap 34 from whence it is conducted by an overflow pipe 35 to the 40 usual sump or the like.

In practice the device is operated in the following manner:—

Fuel is fed to the container 11 through the hopper 12 and, as the fuel is consumed, a 45 fresh charge is delivered to the container by swinging the upper gate 13 open to allow fuel to fill the space between the upper and lower gates. The upper gate is then closed and the lower gate opened allowing the 50 charge of fuel to gravitate to the lower end of the container.

A fire having been started in the grate 3 to ignite the fuel, the worm 20 is rotated, imparting rotation to the container 11 and 55 feeder 6. Fuel will then gravitate from the container 11 to the feeder 6 and from the central opening in the feeder 6 and through the hoods 7 to the fire bed. Because of the rotary motion of the feeder, the fuel will be

distributed by the hoods evenly over the fire 60 bed.

Gases rising from the fire will be trapped in the upper portion of the drum 4 from whence they will pass through the pipes 21 to the super-heater 22. The intense heat of 65 the super-heater will thoroughly dry the green gas and will gasify any particles of coal-tar or creosote which may be contained in the gas and find its way through the pipes into the super-heater.

From the super-heater 22 the gas is conducted through pipe 23 to the washer, as hereinbefore set forth.

Having thus described the invention, what is claimed as new and sought by Letters Patent, is:—

1. A gas producer embodying a drum providing a fire pot and a retort, means for feeding fuel to the drum, a super-heater arranged in the lower portion of the drum 80 and adapted to be buried in the fire bed, means for conducting gas from the upper portion of the drum to the super-heater, and means for conducting the gas from the super-heater.

2. A gas producer embodying a drum providing a fire pot and a retort, a grate, means for feeding fuel to the drum, a super-heater arranged in the lower portion of the drum and buried in the fire bed on the grate, said 90 super-heater being parallel with the grate, means for conducting gas from the upper portion of the drum to the super-heater, and means for conducting the gas from the super-heater.

3. A gas producer embodying a drum providing a fire pot and retort, means for feeding fuel to the drum, a super-heater arranged in the lower portion of the drum and consisting of a flattened tubular member 100 buried in the fire bed, means for conducting gas from the upper portion of the drum to the super-heater, and means for conducting the gas from the super-heater.

4. A gas producer embodying a drum providing a fire pot and a retort, means for feeding fuel to the drum, a grate, a super-heater having a restricted passage and arranged in the lower portion of the drum and parallel to the grate, means for conducting gas from the upper portion of the drum to the super-heater, means for conducting the gas from the super-heater, and means for washing the gas.

In testimony that I claim the foregoing 115 as my own, I have hereto affixed my signature.

FRANK E. MODLIN.
